(57) **CLAIM**

The ornamental design for a set of cuticle shields, as shown and described.

DESCRIPTION

FIG. 1 is a perspective view of one cuticle shield of my new design for a set of cuticle shields, shown separately from the set for ease of illustration;

FIG. 2 is a top plan view of the complete set;

FIG. 3 is a bottom plan view thereof;

FIG. 4 is a left side elevational view thereof, the opposite side being a mirror image;

FIG. 5 is a front elevation view thereof; and,

FIG. 6 is a rear elevation view thereof.
